INVENTOR

Jacob M. Brock

BY

Charles L. Wright
ATTORNEY

UNITED STATES PATENT OFFICE.

JACOB M. BROCK, OF NEW YORK, N. Y.

DOLL-ARM-ACTUATING MECHANISM.

Application filed November 9, 1925. Serial No. 67,723.

This invention relates to improvements in dolls and has as one of its objects to provide a doll having pivotally jointed arms so arranged as to assume different positions in accordance with the posture of the doll body.

A further feature of the invention resides in the application of a removable object to the hand of one arm, whereby an object, such as a simulation of a nursing bottle is automatically moved towards the mouth of the doll when the doll is disposed in a reclining position, and moved away when the doll is upright.

Another aim is in the provision of simple, gravity operated means for actuating the arms into their various positions, the mechanism being of inexpensive construction, readily assembled within a doll body and capable of withstanding the severe use and handling to which such dolls are frequently subjected.

These objects are accomplished by the novel construction and combination of parts hereinafter described and shown in the accompanying drawing, forming a material part of this disclosure, and in which:

Figure 1 is a partial side elevational, partial sectional view of the head and bust of a doll showing the application of the invention.

Figure 2 is a front elevational view of the same.

Figure 3 is a view similar in all respects to Figure 1 but showing the parts in another position.

Figure 4 is a fragmentary sectional view showing the method of attaching the arms to the bust and the means for actuating the arms.

Figure 5 is another view like Figure 1, but showing an alternative actuating means for the arms.

Figure 6 is a fragmentary front and sectional view showing one of the arm connections.

A conventional type of doll head is designated generally by the numeral 10, the same presenting the usual features and is of hollow construction, being made of papier-mâché or similar material in molds or dies, this head being integrally connected by a neck 11 to a bust 12 terminating in a level plane below the shoulders 13.

These shoulders are provided with flat walls 14 arranged in parallel and have passing through them circular openings 15 dis-

posed in alinement and in which the arms are pivoted.

The arms 16 and 17 respectively right and left are bent at the elbows at substantially right angles, the forearms terminating in hands 18 and 19.

Both arms are so shaped as to present flat surfaces at their shoulder junction portions to agree with the corresponding surfaces 14, and are provided with round studs 20, rigidly fixed in the arms to extend through the openings 15 and engage in the ends of a tube extending between them within the confines of the bust, the tube being pinned or otherwise firmly secured to them.

Fixed centrally on the tube 21 is an arm 22 having a weight 23 at its free end, this weight being free to swing within the space between the walls at the throat or neck of the doll, as shown best in Figures 1 and 3, which indicate two different positions of the arm.

In Figure 5 the arm and weight are omitted and a short pendant arm 23 secured to the tube 21, this arm being in position to be engaged by the short end 24 of a lever, the long, pendant end 25 of which carries a weight 26, the lever being pivotally supported by a pin 27 set in the bust as shown. Clearly the weights will move by gravity in the direction indicated by the arrows when the doll is laid down and operate to raise the arm or arms towards the head.

If it be preferred that only one of the arms be moved, the arrangement shown in Figure 6 may be used. In this case the stud 20 may be fitted closely to the opening in the bust, the inner extending end of the stud rotatably engaging the end of the tube and held therein by a pin 28 fixed in the stud and operatively engaging a slot 29 in the tube 21.

The primal idea of the invention is to simulate as closely as possible the action of an infant in moving a nursing bottle to its mouth when laid down and, conversely, when raised to an upright position, to take the bottle from its mouth in a natural manner, both of which features are disclosed in an obvious manner.

It is also regarded desirable to be able to remove the bottle 30 entirely from the hands, the left hand 19 being preferred, and this hand, including the fingers 31 and thumb 32, are so shaped as to constitute a conical

socket or holder in which the bottle may be entered or removed at will.

As changes of construction could be made within the scope of the invention, it is intended that all matter contained in the foregoing description or shown in the accompanying drawings shall be interpreted as illustrative and not in a limiting sense.

Having thus described my invention, 10 what I claim as new and desire to secure by Letters Patent, is:—

1. A doll having a hollow bust flattened at the sides and containing openings in its side walls, a pair of arms having fixed studs 15 revolvably mounted in the openings, a tube rigidly connecting said studs, a lever on said tube, and a weight on said lever, said weight being freely movable within the bust upon change of position thereof.

2. A doll comprising a hollow head and bust, a pair of arms having fixed studs revolvably mounted in said bust, a tube connecting the inner extending ends of said studs, one of said studs being fixed in the 25 tube, the other stud being rotatable in the

tube, means to confine the rotatable stud within the tube, and means including a weight and lever to rotate said tube.

3. A doll comprising a hollow head and bust, a pair of arms having fixed studs revolvably mounted in said bust, a tube connecting the inner extending ends of said studs, one of said studs being fixed in the tube, retaining means permitting the other stud to partially rotate in the tube, a lever 35 arm fixed on said tube, and a weight at the end of said arm freely movable in said bust.

4. A doll comprising, in combination, a hollow freely movable body, an arm carrying a rod rigid herewith, said rod journaled in said body, a weight mounted upon said rod in a position displaced from the axis thereof, forming a bell-crank with said arm and solely controlling the movements thereof whereby upon change of position of said doll to change the position of said arm.

In testimony whereof I have signed my name to this application.

JACOB M. BROCK.
